UNITED STATES PATENT OFFICE.

FREDERICK SCHRAUDNER, OF ST. LOUIS, MISSOURI, ASSIGNOR TO GUS V. BRECHT BUTCHERS' SUPPLY COMPANY, OF ST. LOUIS, MISSOURI, A CORPORATION.

OVERHEAD-RAILWAY SWITCH.

No. 802,119.

Specification of Letters Patent.

Patented Oct. 17, 1905

Application filed June 15, 1905. Serial No. 265,332.

To all whom it may concern:

Be it known that I, FREDERICK SCHRAUDNER, a citizen of the United States, residing in the city of St. Louis, in the State of Missouri, have invented certain new and useful Improvements in Overhead - Railway Switches, of which the following is a full, clear, and exact description, reference being had to the accompanying drawings, forming part of this specification.

My invention relates to a switch for overhead-railway tracks such as are commonly used in factories, stores, and other places for the conveyance of merchandise from one point to another.

Figure I is a top or plan view of my switch with the parts in the positions assumed when the carriage suspended from the overhead track is to be switched onto a side track. Fig. II is a side elevation of the switch with the parts in the positions seen in Fig. I. Fig. III is a top or plan view of the switch with the parts in the positions assumed when the carriage suspended from the track is to be directed on the main track. Fig. IV is a vertical transverse section taken on line IV IV, Fig. I. Fig. V is a vertical transverse section taken on line V V, Fig. III. Fig. VI is a vertical cross-section taken on line VI VI, Fig. II.

1 designates the main-track rails, and 2 a side-track rail, of an overhead railway.

3 designates the hanger of my switch, which is composed of a table member 3, having a ledge 3' and secured to the main-track rails 1, side arms 4 projecting laterally from said table member 3 and having vertical wings 5, the said arms being united by a tie-piece 6. Secured to the vertical wings 5 are guide-plates 7, that are provided with flanges which overhang the upper edges of the wings to furnish guide-ways 8 between the upper edges of the wings and said flanges, in which a part to be herein-after mentioned operates. The arms 4 are provided at their inner ends and at their top side adjacent to the table member 3 with flat runway-surfaces 4'.

9 designates a main-line switch-rail section which is adapted to be brought into alinement or registration with the main-line rails 1 and which rides upon the flat runway-surfaces 4' of the side arms 4 and onto the table member 3. Integral with the rail-section 9 and pro-

jecting rearwardly therefrom is a plate 10, that is provided with guide-arms 11, which 55 operate between and in contact with the side arms 4 to direct the travel of the rail-section when it is reciprocated to and away from the main-line rails.

12 represents tongues projecting downwardly from the rail-section plate 10, as seen most clearly in Figs. IV and V and which are adapted to engage beneath the ledge 3' of the table member 3 when the rail-section 9 is moved into alinement with the main-track 65 rails, whereby said rail-section is held depressed and firmly seated upon the table member.

13 designates a side-track rail-section that when the main-track switch-rail section 9 is 70 retracted is adapted to be moved forwardly onto the table member 3 to place a side-track rail 2 in registration with one of the main-track rails 1, as seen in Figs. I, II, and IV. This rail-section 13 is curved to correspond to 75 the degree of divergency of the side-track rails, and it is integral with a plate 14, the rear portion of which is curved upwardly and backwardly and provided with guide-arms 15, that, in conjunction with the curved portion of the plate, ride in the arc of a circle in the runways 8, provided by the vertical wings of the side arms 4 and the guide-plates 7 fitted to said wings. By this construction provision is made for the travel of the side-track 85 switch-rail section in an upward course of reciprocation above the path of horizontal reciprocation of the switch-rail section 9, whereby each switch-rail section is moved in a path of travel that will avoid conflict with the other 90 switch-rail section.

16 designates a rock-shaft journaled in the rear ends of the side arms 4 of the switch. To this rock-shaft is fixed a lever having a throw-arm 17 extending in one direction from 95 the rock-shaft and a throw-arm 18 extending in the opposite direction from said shaft. The throw-arm 18 is weighted through the medium of a counterbalance-weight 19, located at its termination and provided at one side 100 with a stop-boss 20.

21 is a link pivoted at 22 to the lever-arm 17 and at 23 to ears carried by the switch-rail section 9 and through the medium of which said switch-rail section is reciprocated in a 105 horizontal line to carry it into alinement with

the main-track rails and rearwardly out of alinement with said rails when the lever of which said arm 17 constitutes a part is swung to and fro.

5 24 is a link pivoted at 25 to the lever throw-arm 18 and at 24' to ears 14', carried by the plate of the switch-rail section 13. This link acts to impart reciprocation to the plate 14 and the switch-rail section 13 in a curved course 10 corresponding to the arc of the runways 8, in which said plate 14 travels.

26 is a pull-chain attached to the lever throw-arm 17 and through the medium of which said arm is actuated to swing the lever of which it 15 forms a part to operate the links 21 and 24 to cause them to perform their offices of reciprocating the switch-rail sections to which they are united.

When the parts of my switch are in the positions illustrated in Figs. I, II, and IV, they are 20 located for the travel of the overhead carriage from the main track to the switch-track. To reverse the positions of the switch-rail sections and throw the side-track rail-section 13 out of 25 registration with the main track and the side track and advance the main-line switch-rail section 9 to the main-track rails, the parts are actuated as follows: A pull is exerted upon the chain 26, connected to the lever throw-arm 17, 30 and the lever of which this arm forms a part is rocked from the position seen in Figs. I, II, and IV to the position seen in Figs III and V. As the lever is so moved it acts to draw the side-track rail-section 13 rearwardly, due to 35 the connection between said rail-section and the throw-arm 18 of the lever by the link 24. At the same time the main-track switch-rail section 9 is reciprocated forwardly, due to the connection between the lever and said last- 40 named rail-section provided by the link 21. When it is desired to shift the rail-sections into their former positions, the lever is again thrown into the opposite position by a pull upon the chain 26, thereby causing the links 45 21 and 24 to impart reciprocation to the rail-sections. It will be seen that one rail-section is advanced in such instance while the other is retracted and that due to their moving in different lines of travel there is no conflict in 50 their movement. It will also be seen that the pivot-point 22, at which the link 21 is united to the lever throw-arm 17, is so disposed that when the straight-track switch-rail section 9 is moved to the main-line rails said pivot-point 55 passes the line of dead-center between the rock-shaft 16, that carries the lever, and the pivot-point 23, at which the forward end of the link 21 is connected to the rail-section 9. As a consequence said link is held against 60 accidental movement while said rail-section is in alinement with the main-track rail. The lever is also restrained from movement and the switch-rail section 13 is held retracted while the rail-section 9 is in advanced position, 65 due to the existence of the counterbalance-

weight 19, carried by the lever throw-arm 18. The stop 20, carried by the counterbalance-weight, serves as a restricting member to limit the forward movement of the switch-section 13 when it is moved into advanced position, 70 due to said stop striking against the link 24, as seen most clearly in Fig. IV.

I claim as my invention—

1. In an overhead-railway switch, the combination of a hanger, a main-track rail-section reciprocally supported by said hanger, a side-track rail-section reciprocally supported by said hanger, a rockingly-supported lever, and links independently connected to said lever and one of which is connected to said 80 main-track rail-section and the other of which is connected to said side-track rail-section, substantially as set forth. 75

2. In an overhead-railway switch, the combination of a hanger, a main-track rail-section reciprocally supported by said hanger, a side-track rail-section reciprocally supported by said hanger, a lever rockingly supported intermediate of its ends and consisting of a pair of throw-arms, a link pivoted to one 90 of said throw-arms and loosely connected to said main-rail section, and a link pivotally connected to the other throw-arm and loosely connected to said side-track rail-section, substantially as set forth. 95

3. In an overhead-railway switch, the combination of a hanger provided with vertical wings having curved runways, a rail-section member arranged to travel in said runways and carrying a rail-section, a second rail-section member reciprocally supported by said hanger, and means for reciprocating said first-named rail-section member in a curved path in said runways and said last-named rail-section member in a straight path, substantially 100 as set forth. 105

4. In an overhead-railway switch, the combination of a hanger, a pair of rail-sections reciprocally supported by said hanger, links connected to said rail-sections, and a rockingly-mounted lever comprising throw-arms to which said links are pivoted; one of said throw-arms being provided with a counterbalance-weight, substantially as set forth. 110

5. In an overhead-railway switch, the combination of a hanger, a pair of rail-sections reciprocally supported by said hanger, links connected to said rail-sections, a rockingly-mounted lever comprising throw-arms to which said links are pivoted; one of said throw-arms being provided with a counterbalance-weight, said counterbalance-weight being provided with a stop arranged to engage one of said links, substantially as and for the purpose set forth. 115 120

FREDERICK SCHRAUDNER.
